UNITED STATES PATENT OFFICE.

EDWARD PAUL TOURNIER, OF CHICAGO, AND JOHN FREDERICK WULFF, OF OAK PARK, ILLINOIS, ASSIGNEES TO WESTERN ELECTRIC COMPANY, INCORPORATED, OF NEW YORK, N. Y., A CORPORATION OF NEW YORK.

TOOL.

Application filed April 17, 1925. Serial No. 23,859.

This invention relates to tools, and more particularly to a tool for handling U-shaped elements and has for its primary object the provision of a simple and inexpensive tool for readily and efficiently attaching and detaching different sizes of U-shaped clips or clamping members of the type disclosed and claimed in co-pending application of G. J. Houts, Serial No. 745,093, filed October 22, 1924.

10 In accordance with the general features of this invention there is provided in one embodiment thereof a handle supporting a grooved member, adjustable therein for accommodating clips of different sizes, and carrying at one end thereof means for engaging the clip and co-operating with a resilient member mounted in a grooved post extending from the handle to latchably retain the clip in the grooves.

20 Other objects and advantages of the invention will more fully appear from the following detailed description taken in connection with the accompanying drawings which illustrate one embodiment thereof, and in

25 which

Fig. 1 is a perspective view of a hand tool embodying the features of the invention showing one manner in which it is used fastening a layer of telephone switchboard cables to another layer of cables secured upon a horizontal cable rack;

30 Fig. 2 is an enlarged side elevation thereof showing a clamping member latched thereto, and

35 Fig. 3 is an enlarged vertical sectional view taken on the line 3—3 thereof.

The invention as herein illustrated and described is particularly applicable for use in handling and attaching or detaching the 40 clamping members or clips of the type disclosed in the hereinbefore referred to co-pending application for fastening telephone switchboard cables to each other and to supporting framework but it is to be understood 45 that the novel features of the invention are capable of other applications.

Referring to the drawings wherein like reference numerals designate like parts throughout the several views, 10 indicates 50 a hand grip or handle provided with an integral depending portion 11 and slidably mounted upon guideways or rails 12 formed thereon (Figs. 2 and 3), is a clip or clamp engaging member 13 in the form of a

bar provided upon opposite side faces with 55 grooves 14, within which are entered the rails 12. Integral with the right hand end of the portion 11 of the handle and offset from, and extending below, the lower surface thereof is a post 15 provided with a vertically extending 60 groove 16 (Fig. 2) in its left hand end face which groove is in the same vertical plane with a horizontally extending groove 17 formed in the lower surface of the bar 13 (Fig. 2). As clearly shown in dotted outline in Fig. 2 the groove 17 is cut deeper at both ends than in the intermediate portion, as indicated at 18 and 19, the purpose of which will be set forth hereinafter. At its left hand end, one face of the bar 13 is cut back as indicated 65 at 20 and projecting from a rear wall 23 thereof is a pin 24 adapted to engage within a looped portion 25 at either end of a clamping member or clip 26, the opposite loop 25 resting in the portion 19 of the groove 17 and the 70 upper portion of the groove 16. A more detailed description of the clip 26 may be had by referring to the hereinbefore mentioned application. Mounted in an opening 28 formed in the post 14 below the bar 13 and centered with respect to the groove 15 is a ball 29 which is resiliently held with a portion thereof extending into the groove 15, by a compression spring 30 engaged at its opposite end by a screw 31 threaded into the opening 28. In 75 entering the loop 25 in the grooves 15 and 17, the loop is pressed against the ball 29 which moves inwardly, and then outwardly to the position shown in Fig. 2 thereby latching and securing the clip 26 to the bar 13, the opposite 80 loop having been mounted upon the pin 24 as hereinbefore described. The bar 13 is slidably mounted for adjustment upon the handle 10 for varying the distance between the pin 24 and the ball 29 so that clips of 85 different lengths may be handled by the tool. Upon adjustment of the bar 13 for a certain length clip the bar 13 is retained in its set position upon the rails 12 by a set screw 32 (Figs. 2 and 3) threaded into the post 14. 90

The operation of the tool is as follows:

Referring to Fig. 1 wherein a telephone switchboard cable assembly of a type more fully described in the hereinbefore mentioned patent application is shown, 34 indicates a 105 plurality of cables clamped to a supporting bar 35 by a clamping member or clip 36 having bent or hooked portions 37 at its opposite

ends embracing bar 35 from opposite edges thereof. For a more detailed disclosure of the types of clips used for fastening the first and additional layers of cables, reference may be had to the hereinbefore mentioned patent application. Upon fastening the cables of the first layer to the cross straps 35, a second layer of cables 38 is positioned thereon in the following manner. The operator upon latching 10 a clip 26 in the tool as hereinbefore described grasps the handle 10 thereof as shown in Fig. 1 and engages a hooked portion 40 at the left hand end of the clip 26 with a looped portion 41 of the clamping member 36 as clearly shown in Fig. 1. This is accomplished by tilting the tool first downwardly at the left hand end and giving it a slight movement sideways. Thereafter, by pivoting about the engaged portions in a clockwise direction the opposite hooked portion 40 of the clip 26 may be engaged, in a similar manner, with the other looped portion 41 of the clamping member 36. In engaging the last mentioned hook and looped portions a 25 resilient portion 42 interconnecting the hooked portions 40 is flexed and the enclosed cables are thereby slightly compressed. The deeper portion 19 of the groove 17 is for the purpose of permitting the loop portion of the 30 clip 26 to lie in the same plane as the opposite loop portion which is engaged with the pin 24. The handle may then be raised until the ball 29 passes the associated loop whereupon the pin 24 may be removed from the other 35 loop portion. In detaching a clip from its clamping position, as just described the operator merely engages the tool with the clip to be detached in a manner similar to that of latching a clip to the tool preparatory to 40 attaching a clip in a clamping position as hereinbefore described and then depresses the end of the clip associated with the ball 29 by pressing down upon the handle 10 and upon observing that the associated loop and 45 hook portions of the attached clips are in position to be released, giving the tool a slight movement sideways to cause a complete disengagement thereof whereupon the opposite associated loop and hook portions may be 50 freely disengaged. It is also evident that the tool may be used with equal facility if the cables are suspended from a supporting bar or disposed in a vertical formation. Furthermore, in some cases it may be advantageous, especially where the cables are suspended, to assemble them within the clip retained in the tool, before the clip is attached to a supporting bar or a previously positioned

clip. It is obvious from the foregoing description of the use of the tool in handling 60 and attaching or detaching the clip 26 that the clip 36 may also be readily handled thereby for attaching it in a clamping position upon the strap 35 or detaching it therefrom.

From the foregoing description it will be 65 seen that the tool described is of comparatively simple formation in its construction and the arrangement of its parts and that it can be operated with very little skill on the part of an operator. It will be clearly understood that the tool can be used for different types of clamping members for different purposes, although particularly devised and illustrated in the drawings for use with the clamping member of the type disclosed 75 in the hereinbefore mentioned application.

What is claimed is:

1. A tool comprising a handle, and means carried thereby for latchably engaging a U-shaped element, said means comprising oppositely disposed fixed and resiliently actuated means for engaging the side portions of the element. 80

2. A tool comprising a handle having guideways therein, a member adapted to slide 85 upon said guideways for adjusting the tool for different sized elements, said member adapted to support an element at one end thereof, and means carried by the handle for resiliently supporting the opposite end of the element. 90

3. A tool comprising a handle, means carried thereby for entering within a U-shaped element, and resiliently actuated means for latchably engaging the exterior of the element to thereby retain the element associated 95 with the handle.

4. A tool comprising a handle, and means carried thereby for latchably engaging a U-shaped element, said handle and means provided with co-operating grooved faces disposed at an angle to each other for guiding the element into and from a latched position. 100

5. A tool comprising a handle, and means carried thereby for latchably engaging a U-shaped element, said means comprising a pin 105 carried by the handle and extending laterally at one end thereof for entering within the element and a co-operating spring pressed ball mounted substantially opposite thereto in a grooved face of the handle for engaging 110 a side portion of the element to retain the element associated with the handle.

In witness whereof, we hereunto subscribe our names this 13th day of June A. D., 1925

EDWARD PAUL TOURNIER.
JOHN FREDERICK WULFF.
